UNITED STATES PATENT OFFICE.

OTIS T. CRAFTS, OF MANCHESTER, NEW HAMPSHIRE, ASSIGNOR TO CRAFTS PROCESS,
INC., OF MANCHESTER, NEW HAMPSHIRE, A CORPORATION OF MAINE.

PROCESS OF MAKING HEEL BASES.

Application filed February 19, 1927. Serial No. 169,629.

My present invention relates to heel bases, particularly adapted for use in the manufacture of boots and shoes, more particularly such shoes utilizing rubber heels, and includes also the novel process of manufacturing such heel base.

In my prior Patents, No. 1,458,524 dated June 12, 1925, and No. 1,528,912 dated March 10, 1925, and in my prior and co-pending applications Serial No. 56,112, filed September 14, 1925, Serial No. 164,207, filed January 28, 1927, and No. 164,208, filed January 28, 1927, I have illustrated and described various forms of heel bases with a uniform rand-like rim on the bottom or shoe engaging surface of the base, as well as novel rands for use therewith.

The blanks, rands, and bases described in said patents and applications may be, and preferably are, made from extremely cheap, inexpensive material, frequently being constructed from scrap or waste leather. In my development of this art, however, I have discovered a novel method of manufacturing a randed heel base, utilizing material for which there has heretofore been known no useful application.

An important object of the present invention, therefore, is the provision of a heel base applicable for use in all classes of boot and shoe making, which will embody all of the features of high priced bases, while at the same time being constructed from material or stock which has heretofore been considered as absolute waste.

During the process of cutting, stamping, or dieing out lifts, whether whole or half section lifts, there are left over numerous portions, pieces, or strips of leather, frequently leather of the highest grade. These strips or pieces, heretofore, have been discarded as useless and valueless, since they were too small to provide for the cutting therefrom of even a half lift section. I have discovered, however, that these heretofore waste strips contain sufficient material from which may be severed or die the pieces or sections utilized in carrying out my present invention.

The present invention consists in building a heel base blank, preferably comprised of a plurality of lifts or layers. One of the layers of this heel base is composed of a plurality,

preferably three or more sections or pieces cut, according to my present invention, from the leavings or scrap leather resulting from various cutting and dieing operations. When assembled, and regardless of whether the layer comprised of the plurality of small sections is on the top, bottom, or interposed between the top or bottom layers, a rand-like rim is bevelled into the blank, producing a suitable concavity for contact with the heel seat surface of the shoe. As fully explained in my prior patents and applications, this eliminates the expensive and costly methods of applying separate rands to a heel base blank. The blank of my present invention, if built to a height greater than that required for a finished heel base, may be skived or levelled to finished predetermined height, as fully described in said prior patents and applications. In cutting or dieing out the pieces or sections utilized for one layer of my novel heel base, I have discovered that a single die may be utilized for forming the pieces positioned at the sides of the heel base blank, these pieces conforming to the slight curve at the side of the heel blank, and being interchangeable with each other. Also, these side pieces, so formed by a single die, may be applied, for example, in bases for men's shoes, to every size of heel, the only change in size of lift material being that required for the strip, section or piece which is positioned at the back of the heel, or the portion opposite the heel breast.

Thus I produce a novel heel base, frequently constructed from expensive leather stock, but from pieces of said stock which have heretofore been considered as waste, and therefore valueless and useless. I am not limited, of course, to the use of such pieces of scrap from high grade leather, but may use other grades of stock. In finished condition and appearance, my novel heel base presents as attractive an appearance as a heel base made from whole and expensive lifts, and will stand up, under wear, equally as efficiently as such an expensive base.

I believe that my present heel base, as well as the method of manufacturing same, is novel, and I have therefore claimed both the process, and the article produced thereby, in the present application.

Further features of the invention, details, advantages, and combinations of parts, will be hereinafter more fully pointed out and claimed.

5 Referring to the drawings, illustrating preferred embodiments of the present invention,

Fig. 1 is a plan view of a strip of waste material illustrating the method of cutting

10 my pieced lift sections therefrom;

Figs. 2 and 3 are perspective views of the pieces cut therefrom;

15 Fig. 4 is a plan view of a plurality of heel sizes illustrating the application of the pieced lift sections thereto;

Fig. 5 is a perspective view of a blank formed according to my present invention;

20 Fig. 6 is a perspective view of the completed heel base with the bevelled concavity formed therein;

Figs. 7 and 8 are perspective views of modified forms of pieces or sections utilized for the back part of the heel;

25 Figs. 9 and 10 are perspective views of finished heel bases utilizing the sections of Figs. 7 and 8 respectively;

Fig. 11 is a perspective view of a modified form of heel blank;

30 Fig. 12 is a perspective view of the completed base formed from the structure of Fig. 11;

Fig. 13 is a perspective of a still further modified form of heel blank; and

35 Fig. 14 is a perspective of the completed heel base formed therefrom.

As shown in the drawings, 1 designates a strip or piece of leather resulting from the dieing out from a sheet of leather of heel lifts, soles, or the like. These pieces of leather 1 have been considered too small for any practical purpose, they not presenting sufficient area from which to cut a half lift section, which heretofore has been considered the smallest possible piece or section from 40 which heel bases or the like could be constructed.

However, for the purpose of carrying out my present invention, I have discovered that the pieces 1 present sufficient area to enable 50 me to cut or die therefrom the sections from which I construct at least one layer or lift of my novel heel base. For example, from the piece 1 I may die out the pieces 2 and 3, more clearly illustrated in Figs. 2 and 3.

55 The piece or marginal section here illustrated as 2, presents numerous advantageous features. As shown in Fig. 4, these pieces 2 are applied to the outside edges of a lift 4. The lift 4 is approximately the smallest size 60 of lift which can be utilized in a man's shoe. The lifts 5, 6, 7 and 8 represent larger sizes of heel lifts suitable for men's shoes, up to approximately the largest size practical. A peculiarly advantageous feature of the sections 2, cut in the form as shown, with one

edge 9 having a slightly arcuate contour, and the opposite edge 10 being substantially straight, is that these sections 2 are interchangeable for either side of the lift to which they are applied. This adaptability is clearly shown in Fig. 4, it being immaterial to which side of the lift 4 the operator applies the sections 2, so long as the arcuate edge 9 is on the outside. Thus, I am enabled to utilize a single die to cut the side 75 marginal sections 2 for all sizes of men's heels, as shown herein. The same advantages will be present in the making of women's or children's shoes, and I am not, of course, limited to the use of my invention in men's shoes, this construction being shown in the present application for illustrative purposes only.

It will, of course, be necessary to vary the size of the rear marginal section 3 for the varying sizes of heel lifts or pieces, but the marginal sections 2 remain the same. The sections 2 and 3 are of sufficient width, so that when bevelled to form the heel seat concavity, there will still remain a sufficient 90 marginal width of material to receive the heel nails.

Fig. 5 illustrates, in perspective, a heel base blank constructed according to my present invention. In this form, the side marginal sections 2 and the rear marginal section 3 have been applied to a single lift 11. The sections 2 and 3 abut along distinct substantially perpendicular lines 12 as clearly shown. The sections 2 and 3 are cemented, glued, or otherwise adhered to the lift 11. The blank is then subjected to a beveling or gouging action, to produce the concavity desired in the particular heel base under construction, which beveling action produces the heel base illustrated as 13 in Fig. 6. This bevelled heel base may be compressed, molded, or finished, as desired.

It will thus be seen that I have devised a novel heel base, comprising a plurality of 110 predetermined marginal sections, so constructed and arranged as to present an unbroken marginal portion or edge at the rear of the heel. This is of advantage, since it eliminates any cracking or breaking of the heel at this point, resulting in a much 115 stronger and more firmly united heel base.

In Fig. 11 I have illustrated a heel base blank constructed of the marginal sections 2 and 3, assembled on a lift 11, but with an additional lift at the top of the blank. This top lift comprises, in the present instance, two half sections 14 and 15. If desired, of course, a single lift can be utilized in place of the two sections 14 and 15, but the construction herein illustrated in Fig. 11 lends the advantage of increased economy to the manufacture of such a heel base blank.

In Fig. 12 is clearly illustrated the bevelled base constructed from the blank of 130

Fig. 11. The rand-like rim formed in the marginal sections 2 and 3 will be readily apparent.

It will frequently happen that the died out sections 2 and 3 will be too thin to be positioned on the bottom of the blank, and receive the bevelling action. In this event, it is within the province of my present invention to form a heel base blank as illustrated in Fig. 13, wherein the sections 2 and 3, being too thin for the bevelling of the rand-like rim, are adhered or secured to a lift 16. Over the sections 2 and 3 is fitted and adhered a further lift or layer, which may comprise a single lift or as illustrated in the present instance a pieced lift comprising two half sections 17 and 18.

The completed base, formed from the blank of Fig. 13, is illustrated at 19 in Fig. 14. This form of base has a very sturdy construction, capable of withstanding the strains and wear incurred in boot or shoe usage.

In the event that the waste strip 1 may not present sufficient area from which to form the rear section 3, it may still be possible to cut therefrom a section 20, illustrated in Fig. 7, or a section 21, as illustrated in Fig. 8. In Fig. 9 is illustrated a heel base formed by utilizing the sections 20, wherein two of the sections 20 are applied to a lift 22. These sections 20 may be, and preferably are, cut with a single die into two identical sections, meeting at the center of the rear of the heel approximately at the point 23. In the form shown in Fig. 9 the side marginal sections 2 are also utilized.

The rear marginal sections 21 are also preferably cut with a single die, thus providing two identical members. When applied to a lift 24, as illustrated in Fig. 10, these two sections 21 will meet at the center of the rear of the base at the point 25. The side marginal sections 2 are equally applicable to this form. It will be instantly apparent that the rear marginal sections 21, being died out in such manner as to eliminate all unnecessary material, for example at the point 26, may be cut from extremely

small pieces of scrap or waste leather, and thus represent a still further saving in the cost of my novel heel base.

It will thus be apparent that, although I utilize in the manufacture of the heel base of the present invention, material which is extremely economical, due to the fact that there are no other apparent usages for the same, I have produced a heel base which can be manufactured at extremely reasonable cost. At the same time, the heel bases constructed according to my invention will stand up in wear, will take the edge finishing, burnishing, inking, and any other operations to which expensive and high grade heel lifts may be subjected.

While I have necessarily described my present invention somewhat in detail, it will be appreciated that I am not limited thereto, but may vary the size, shape, and arrangement of parts, within reasonably wide limits, without departing from the spirit of the invention.

My invention is further described and defined in the form of claim as follows:

The improved process of making heel bases of different sizes, which consists in assembling a plurality of predetermined marginal sections on a lift, said sections forming one layer of a blank and abutting at a plurality of points, two of said marginal sections being applied at the sides of said lift and substantially flush therewith and being substantially identical in contour and size regardless of the size of lift to which they are applied, and a third section being applied at the rear of said lift and presenting an unbroken marginal portion at the rear of the blank, said third section only, of the said predetermined marginal sections, varying in size with the varying sizes of lifts to which said marginal sections are applied, forming said blank to desired height, and thereupon forming a rand-like rim in one of said layers.

In testimony whereof, I have signed my name to this specification.

OTIS T. CRAFTS.
